UNITED STATES PATENT OFFICE

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY

AUTOMATIC REGULATING DEVICE FOR BOILERS

Application filed July 27, 1928. Serial No. 295,648.

My invention relates to improvements in regulating means for heating apparatus and the same has for its object to provide a simple, efficient and reliable automatic device for controlling the operation of dampers in a boiler.

Further, said invention has for its object to provide a device formed as a unitary structure which may be secured directly to a steam heating boiler.

Further, said invention has for its object to provide a unitary device consisting essentially of a cover plate which is adapted to seal the opening in a boiler, and which also serves as a support or carrier for the pressure responsive element and its associated parts.

Further, said invention has for its object to provide a unitary device whose pressure responsive element is adapted to extend through an aperture in the boiler and into the fluid space thereof, and in which the support for said pressure responsive element serves as a cover plate to seal the receiving aperture of the boiler.

Further, said invention has for its object to provide a device of the character specified in which the expandible-collapsible element, the supporting cover-plate therefor, the operating lever and its support, and the actuating element interposed between said expandible-collapsible element and said operating lever are all formed as a unitary structure to facilitate the easy attaching to, or removal of the device from a boiler or heating apparatus.

Other objects will in part be obvious and in part be pointed out hereinafter.

To the attainment of the aforesaid objects and ends my invention consists in the novel features of construction, and in the combination, connection, and arrangement of parts hereinafter more fully described and then pointed out in the claim.

In the accompanying drawings—

Figure 1 is a side elevation of a domestic steam heating boiler equipped with one form of regulating device constructed according to and embodying my said invention;

Fig. 2 is an enlarged detail central sec-

tion showing the upper portion of a boiler and regulating device, and

Fig. 3 is a top view thereof.

In said drawings, 10 designates a sectional steam heating boiler of the type generally used for domestic heating purposes. The boiler is provided at its front with the usual openings provided with doors 12, and at the rear of the back section with a smoke hood 13 having a check damper 14, and at the base of said rear section with a main air inlet 15 having a hinged door or damper 16.

The rear section of the boiler is provided at its top or upper portion with an aperture 17 into which is fitted an automatic pressure responsive device 18. The said aperture 17 is provided with an annular recess 19, and a plurality of laterally-projecting bifurcated members 20.

21 denotes a cover plate having a central, threaded, aperture 22 extending therethrough, and an annular rib 23 extending from the under side of said cover plate adapted to be received by the annular recess 19 of the aperture 17 in the boiler.

Within the threaded aperture 22 of the cover plate 21 is secured one end of a tubular post or support 24 having a closed upper end provided with a reduced opening 25, and laterally extending bearing members 26 within which is pivotally supported an operating lever 27 which is operatively connected at one end with said check damper 14 and with said main air inlet door or damper 16 by a rod 28. The tubular post 24 is provided intermediate its ends with a polygonal portion 24^a to receive a suitable tool or wrench for securing said post 24 in the cover plate 21.

29 denotes an expandible-collapsible element, preferably in the form of a transversely corrugated metal vessel having a closed inner end provided upon its inner side with a threaded boss 30, and having its outer end open and terminating in a laterally-projecting integral flange 31 adapted to extend into and rest upon the recessed portion 19 of the aperture 17 in the boiler.

32 denotes bolts whose heads 33 are loosely engaged by the bifurcated members 20 of the boiler. The threaded upper ends of said

100

bolts extend through suitable apertures in the cover plate 21 and are provided with nuts 34, which, when screwed down, serve to secure the cover plate 21 firmly in place to seal the aperture 17 in the boiler, and at the same time secure the flange 31 of the expansible-collapsible element 29 firmly clamped in position between the under side of the annular rib 23 of the cover plate and the recess 19 of the opening 17.

35 denotes a stem having its inner end threaded and secured within the threaded boss 30, and its other end extending upwardly within said expansible-collapsible element 29 and through the cover plate 21 and hollow post 24, and has its free end, which projects out of said hollow post, adapted to engage with the under side of said operating lever 27 when said stem 35 is actuated by the compressing or collapsing of the expansible-collapsible element 29. The said stem 35 is provided within the tubular post 24 with a shoulder 36, and at its projecting portion with a transverse pin 37, which shoulder and pin serve as stops to limit the collapsing and expanding movements of the expansible-collapsible element 29 of the stem 30 in response to pressure variations obtaining within the fluid space of the boiler.

30 The lever 27 is provided intermediate its free end and pivoted portion with a counter weight 38 which is adjustably secured in position by a lock screw 39.

The operation of the apparatus will be obvious from the foregoing specification. It need merely be noted that when the expansible-collapsible element is compressed or collapsed in response to pressure increase within the boiler, the stem 35 will be caused to move upwardly or outwardly and the projecting end thereof engage the under side of the lever 27 between its free end and the pivoted support therefor, and raise said end, and accordingly depress its opposite end, thereby causing the rod 28 to descend and close the draft inlet door 16 and open the check damper 14 in the smoke hood 13. When the pressure within the boiler again decreases in response to a décrément in the temperature of the water due to the reduced rate of combustion, the opposite operation from that above described will take place.

It is to be noted particularly that my pressure responsive device, i. e., the parts comprising the cover plate 21, expansible-collapsible element 29, stem 35, and support 24 are combined as a unitary structure and may, as such, be attached to, or removed from the boiler by merely manipulating the bolts 32, and that the said bolts 32 simultaneously serve to secure the cover plate 21 in place to seal the opening 17 in the boiler, and to secure the expansible-collapsible element 29 in position within the opening 17 in the boiler.

Having thus described my said invention,

what I claim and desire to secure by Letters Patent is:

The combination of a heating apparatus having an opening therein provided with an annular recess and communicating with the fluid space of the heating apparatus with a regulating device comprising a cover plate, an annular rib on the under side of said cover plate, a tubular support on said cover plate and extending outwardly therefrom, a lever pivotally mounted on said tubular support, an expansible-collapsible vessel having a closed movable inner end, and a laterally extending flange at its outer end supported within the annular recess of the opening in said heating apparatus, means for securing said cover plate to the heating apparatus in position over the opening therein and clamping the laterally-extending flange of said expansible-collapsible element between the annular rim on said cover plate and the base of the annular recess surrounding said opening, a stem having one end extending into said expansible-collapsible element and secured to the closed movable end thereof, and having its other end extending outwardly through said expansible-collapsible vessel and through said tubular support and adapted for engagement with said lever whereby to actuate the same in response to changes in thermal conditions obtaining within the fluid space of the heating apparatus, and stops on said stem adapted to engage with the outer end of said tubular support for limiting the excursion of said stem, substantially as specified.

Signed at the city of New York, in the county and State of New York, this 22nd day of June, one thousand nine hundred and twenty-eight.

ANDRÉ M. MERTZANOFF.
